UNITED STATES PATENT OFFICE.

CLARENCE L. GERRARD, OF COLUMBUS, NEBRASKA,

GAS-GENERATOR

No. 836,495.

Specification of Letters Patent.

Patented Nov. 20, 1906.

Original application filed October 18, 1905, Serial No. 283,248. Divided and this application filed February 23, 1906.
Serial No. 302,414.

To all whom it may concern:

Be it known that I, CLARENCE L. GERRARD, a citizen of the United States, and a resident of Columbus, in the county of Platte and State of Nebraska, have invented a new and Improved Gas-Generator, of which the following is a full, clear, and exact description.

The present application is a division of my former application, Serial No. 283,248, filed October 18, 1905.

The invention relates to certain peculiar features of construction and arrangement of parts concerned with an apparatus for generating nitric oxide or other gas, all of which will be fully set forth hereinafter and particularly pointed out in the claims.

Reference is to be had to the accompanying drawings, which illustrate, as an example, the preferred embodiment of my invention, in which—

Figure 1 is a vertical section of the generator. Fig. 2 is a detail view showing the case in which the acid-receptacle is held, and Fig. 3 is a reduced vertical section through the case in which the acid-receptacle is held.

The apparatus is intended especially for use in connection with the treatment of wheat or flour wherein the nitric oxide or other gas is mixed with air and the mixture brought into intimate association with the flour or wheat while the gases are in a nascent condition.

19 indicates an air-supply pipe, and 20 indicates the discharge-pipe for the nitric oxide or other gas. The pipe 19 has at its end a coupling 22, which is engaged with a pipe-section 23, secured in the generator-head 24, the pipe 20 passing from the head 24 opposite the pipe 23. Said union 22 also secures in

position within the pipe-section 23 a tapering nozzle 25, which causes the air to be discharged into the head 24, and thus causing the velocity of the air to increase by expansion as it passes through the head into the pipe 20. Said head 24 supports a box or casing 26, which, as best shown in Fig. 4, has an opening 27 in its top, this opening passing from the top of the casing outward to the side edge thereof. Matching with the opening 27 is an opening 28 in the head 24. (See Fig. 3.) One side of the casing or box 26 is open, as indicated at 29 in Figs. 1 and 2, and this opening is adapted to be closed by a semicircular door 30. (See Fig. 2.) The door 30 has a lip 31 at its upper edge adapted to

close the opening 27, the lip being elevated so as also to close the opening 28 in the head 24. (See Fig. 3.)

32 indicates a jug or receptacle for holding the nitric-acid solution. This receptacle is formed, preferably, of porcelain or some other refractory material and has an open neck 33, which is adapted to fit in the opening 28 in the under side of the head 24. Said receptacle or jug 32 is placed in position in the case 26 by opening the door 30 and moving the receptacle 32 sidewise into the case, the neck 33 sliding through the openings 27 and 28 into the position shown in Figs. 1 and 3.

Fitting loosely in the neck 33 of the receptacle 32 is a porcelain or other acid-resisting tube 34, which has an open upper end and a flange 35 surrounding it, which flange rests on the neck 33 of the jug. The lower end of

the tube 34 is closed, and said tube is provided with a lower opening 36, an upper opening 37, and two intermediate openings 38. These openings communicate with the interior of the jug or receptacle 32. At its upper side the head 24 is provided with a stuffing-box and gland 39, through which the metallic rod 40 passes loosely, said rod projecting through the head downward into the tube 34 and resting on the close lower end thereof, the arrangement being such that during the operation of the apparatus the rod 40 is free to move downward into the tube 34 by force of gravity as fast as the said rod is attacked and disintegrated by the action of the acid thereon. 41 indicates a thumb-screw by means of which the rod 40 may be held against this movement when the device is not in operation.

Upon supplying the receptacle 32 with nitric-acid solution and introducing the rod 40 into the tube 34 the solution will enter the tube 34 through the opening 36, and in attacking the rod 40 the gases will be generated which will pass up into the head through the tube 34, mixing with the air therein. The rod 40 may be of various metals, among which may be mentioned galvanized iron. As is well known, in order that the acid may readily attack the rod of iron or other metal it is necessary that such attacking acid be maintained at a temperature considerably higher than the normal temperature of said acid. This is especially true where the apparatus is located in an unheated room dur-

ing the colder seasons of the year. In many forms of apparatus it is, therefore, necessary to apply heat from external sources to the solution both at the beginning of the operation and continuously during the generation of the gas. With my apparatus, the generation of the gas having once been started the heat developed by the chemical reaction is conserved and is sufficient to maintain the acid surrounding the rod continuously at a temperature at which it readily attacks the metal. The acid within the tube 34 is thus automatically kept at a much higher temperature than the main body of the solution. The reactions in the lower part of the tube 34 develop heat, which causes the generation of gas and also causes the solution to circulate through the opening 36 and up out of the openings 38. The upper opening 37 allows for overflow should the solution rise excessively in the tube and prevents the solution from entering the head 24 of the apparatus. The air passing through the head 24 will gather the gas generated, and the mixture will then pass through the pipe 20 to the desired point. In connection with the manner of feeding the rod 40 it will be seen that said rod rests by force of gravity on the closed lower end of the tube, and as fast as the rod is disintegrated it will fall into the tube. In this manner the rod is kept submerged at a uniform depth, and a uniform generation of gas results.

Having thus described the preferred form of my invention, what I claim as new, and desire to secure by Letters Patent, is—

1. A gas-generating apparatus comprising a receptacle for acid, an open-mouthed tube having its lower end projecting into the acid in said receptacle, said tube having a portion constructed and arranged to support a metallic rod inclosed therein, said tube having perforations therein at various distances along its length, and a generator-head inclosing the upper end of the tube, said head having an opening through which said rod is fed into said tube.

2. The combination with an acid-containing vessel having an open mouth, of a generator-head inclosing said mouth, said head having an opening, in alinement with said mouth, through which a metallic rod may be fed into the acid contained in said vessel.

3. The combination with an acid-containing vessel, of an open-mouth tube, projecting into the acid in said vessel, the submerged end of said tube having an opening therein, and a generator-head inclosing the mouth of said tube, said head having an opening in alinement with said mouth through which a metallic rod may be fed into the acid contained in said tube, said tube serving to support the lower end of the rod and to conserve the heat resulting from the chemical reaction of the acid on the metal.

4. The combination with an acid-containing vessel, of an open-mouth tube supported about the opening in said vessel, and projecting into the acid contained therein, and a generator-head inclosing the mouth of said tube, said head having an opening in alinement with said mouth, through which a metallic rod may be fed into the tube, said tube being provided with a plurality of perforations, one in its submerged portion to permit the flow of acid into the tube and another above the surface of the acid to prevent the outflow of the acid through the mouth of the tube.

5. The combination of a generator-head having an opening extending from its bottom to one side of the head, a case having an opening in its top registering with the opening in the generator-head, the side of the case having an opening therein, a closure for said opening, a solution-receptacle having a neck adapted to fit in the opening in the generator-head, and a perforate tube projecting through the neck of the receptacle and having an open upper end communicating with the head.

6. The combination of a generator-head having an opening extending from the bottom to one side of the head, a case supported by the generator-head and having an opening in its top registering with the opening in the head, the side of the case having an opening therein, a closure for said opening, a receptacle for an acid solution having a neck adapted to fit in the opening in the bottom of the generator-head, a perforate tube of acid-resisting material fitting loosely in the neck of the receptacle and having an open upper end, communicating with the generator-head, the said tube being closed at its lower end and extending into the acid solution in said receptacle, the said generator-head having an opening in its upper side in alinement with the said tube, and a metallic rod resting at its lower end on the bottom of said tube, and extending loosely through the said opening in the upper side of the generator-head.

7. A gas-generator comprising a generator-head having an inlet-pipe connected with one side thereof, and an outlet-pipe leading from the opposite side, the said generator-head having an opening in its bottom, a case supported by the generator-head and having an opening in its top registering with the opening in the bottom of the generator-head, a receptacle for acid solution in said case and having an open neck adapted to fit in the opening in the bottom of the head, a tube located in the receptacle and having an open upper end communicating with the generator-head, the tube being provided with a flange surrounding the open upper end and resting on the neck of the said receptacle, the said tube being closed at its lower end, and

provided with perforations in its sides, the said generator-head having an opening in its top in alinement with the said tube, and a metallic rod passing loosely through said opening and extending through the head into the said tube and resting on the closed lower end thereof.

8. A gas-generator comprising a generator-head having an opening in its bottom, a case supported by the generator-head and having an opening in its top registering with the opening in the bottom of the generator-head, a receptacle for acid solution in said case and having an open neck adapted to fit in the

opening in the bottom of the head, a tube extending into the receptacle and resting at its open upper end on the neck of the receptacle, the tube having side openings and a closed lower end capable of supporting a metallic rod, and means on the head for loosely holding the rod in place.

In testimony whereof I have signed my name to this specification in the presence of two subscribing witnesses.
